UNITED STATES PATENT OFFICE

149,485

DESIGN FOR A CASING FOR A CHRONO-METRIC RECORD DEVICE

Albert E. Grant, Kansas City, Mo.

Application August 1, 1946, Serial No. 132,167

Term of patent 7 years

(Cl. D64—11)

To all whom it may concern:

Be it known that I, Albert E. Grant, a citizen of the United States, residing at Kansas City, in the county of Jackson and State of Missouri, have invented a new, original, and ornamental Design for a Casing for a Chronometric Record Device, of which the following is a specification, reference being had to the accompanying drawing, forming part thereof, in which

Fig. 1 is a front perspective view of a casing for a chronometric record device, showing my new design, and

Fig. 2 is a rear perspective view of the casing shown in Fig. 1.

The essential features of my design reside in the part shown in full lines.

I claim:

The ornamental design for a casing for a chronometric record device, substantially as shown and described.

ALBERT E. GRANT.
